UNITED STATES PATENT OFFICE.

LOREN W. PENNEY, OF NEWTON HIGHLANDS, MASSACHUSETTS, ASSIGNOR TO SACO-LOWELL SHOPS, OF BOSTON, MASSACHUSETTS, A CORPORATION OF MASSACHUSETTS.

COILER.

Application filed April 10, 1925. Serial No. 22,070.

This invention relates to coilers of the type used in textile mills to coil the sliver into a can immediately after the sliver comes from a carding machine.

5 A coiler includes a bar, commonly called a "tongue", which is provided with a tapered hole, known as a "trumpet" through which the roving is guided to the feed rolls of the coiling mechanism. This tongue is 10 pivoted at the back of the mechanism and fits in a slot formed in the cover or "bonnet" of the machine. The tongue and bonnet should fit together tightly without leaving any open crack or crease between them, and 15 for this reason each tongue must be fitted to the particular bonnet with which it is to be used. The upper surface of the tongue is made level with the corresponding surface of the bonnet and both surfaces are polished forming, in effect, a continuous surface.

This construction not only is relatively expensive to manufacture, but it is a particularly expensive matter to replace a broken tongue. Oftentimes it is necessary to send a machinist to the mill in which the broken coiler is installed to replace the tongue and fit it properly into the bonnet. It is the 25 chief object of the present invention to overcome this difficulty. That is, the invention aims to devise a construction in which the tongues will be interchangeable so that any special fitting of an individual tongue to a bonnet will be eliminated. It is also an object of the invention to facilitate the inspection 30 of the machine during operation.

The nature of the invention will be readily understood from the following description when read in connection with the accompanying drawings, and the novel features 40 will be particularly pointed out in the appended claims.

Referring now to the drawings,

Figure 1 is a plan view of a coiler with certain parts of the bonnet broken away;

Fig. 2 is a vertical cross sectional view through the upper part of the coiler shown in Fig. 1; and

Fig. 3 is a perspective view of a part of the 50 tongue provided by this invention.

The machine shown includes a vertical shaft 2 carrying a pinion 3 which drives a gear 4 formed integral with the coiler tube 5. Secured on the upper end of the shaft 2

is a bevel gear 6 driving another bevel gear 7 which is fast on the feed roll shaft 8. A pinion 9 integral with the bevel gear 7 drives the other feed roll shaft. The two feed rolls are indicated at 10 and 12, respectively.

The tongue 14 is pivoted at 15 between the ears of a bracket 16, and it is provided with a trumpet 17 to guide the roving or sliver R downwardly between the feed rolls 10 and 12. This tongue is normally held in its operative position by gravity, the forward end of the tongue being weighted or thickened, as shown at 18. It is provided on its lower surface with two lugs or feet 19 and 20 which rest on the bearing brackets for the roll shafts.

The bonnet 21 is pivoted to the rear of the machine at 22. This bonnet, unlike the usual constructions, is provided with a long slot 23 extending from front to rear, and the metal of the bonnet surrounding the slot is turned downwardly, as clearly shown at 24 in Fig. 2, and rests on the tongue 14. The upper surfaces of both the tongue and the bonnet are polished, and the tongue has a flat top on which the lower flat edge of the rim 24 rests, forming a comparatively tight joint between these parts.

The slot in the bonnet is made so long that the bonnet can be tipped backwardly into its inoperative position, as indicated by dotted lines in Fig. 2, without interfering with the feeding movement of the roving or sliver, the sliver simply taking a somewhat different path at the back of the machine, as indicated at R'. This is an important advantage 80 in permitting the operator to inspect the action of the machine without interrupting its operation.

In order to enable the workman to observe the feeding of the sliver between the trumpet and the feed rolls, I have disposed the weighted or enlarged portion 18 at the forward end of the tongue chiefly on one side of the median line of the tongue, thus leaving a space between the part 18 and the foot 20, as shown in Fig. 1, through which the operator can see the lower end of the trumpet 17 when the bonnet is lifted but while the tongue is in its normal position. This is an advantage after piecing 105 up, since it enables the operator to tell whether or not the sliver is being fed properly.

Due to the fact that the bonnet simply rests on the tongue without fitting around it, as in prior constructions, the tongues can all be made alike so that they are interchangeable. This is an important advantage in manufacture and it is an even greater advantage in replacing broken tongues, since it eliminates any necessity for fitting a tongue to an individual bonnet, as has been required heretofore. The weighting of the end of the tongue also does away with the spring latch that has been used heretofore to hold the tongue in its operative position.

While I have herein shown and described the best embodiment of my invention that I have so far devised, it is contemplated that minor modifications may be made without departing from the spirit or scope of the invention.

Having thus described my invention, what I desire to claim as new is:

1. In a coiler, the combination of coiling mechanism, a tongue having a trumpet for guiding a sliver to said mechanism, and a bonnet for protecting said mechanism, said bonnet overlying said tongue and having a long slot therethrough extending from front to rear and closed by said tongue, said slot being sufficiently long to allow the bonnet to be tipped into its backward position without interfering with the feeding of the sliver.

2. In a coiler, the combination of coiling

mechanism, a tongue having a trumpet for guiding a sliver to said mechanism, and a bonnet resting on said tongue, said tongue having a smooth flat upper surface, and said bonnet having a slotted portion surrounded by a smooth lower face to bear on the upper surface of said tongue.

3. In a coiler, the combination of coiling mechanism, a pivoted tongue having a trumpet for guiding the sliver to said mechanism, the forward end of said tongue being weighted, and a bonnet pivoted at the back of the machine and having a long slot therethrough extending from front to rear with the lower face of said tongue around said slot resting on said tongue.

4. In a coiler, the combination of coiling mechanism, and a pivoted tongue having a trumpet for guiding the sliver to said mechanism, the forward end of said tongue being weighted, with the weighted portion disposed chiefly at one side of the median line of the tongue so that a view of the trumpet is afforded under the end of the tongue and past said weighted portion.

5. In a coiler, the combination of coiling mechanism, a tongue having a trumpet for guiding the sliver to said mechanism, and a bonnet overlying said tongue and mounted to swing upwardly away from the tongue, said bonnet having a slot through which the sliver can travel to the trumpet.

LOREN W. PENNEY.
